US0D1113727S

(12) **United States Design Patent** (10) **Patent No.:** **US D1,113,727 S**
(45) **Date of Patent:** **** Feb. 17, 2026**

(54) **INDUCTOR PACKAGE**

- (71) Applicant: **Vishay Dale Electronics, LLC**,
Columbus, NE (US)
- (72) Inventors: **Benjamin M. Hanson**, Lennox, SD
(US); **Tyler Witzel**, Yankton, SD (US)
- (73) Assignee: **Vishay Dale Electronics, LLC**,
Columbus, NE (US)
- (**) Term: **15 Years**
- (21) Appl. No.: **30/006,183**
- (22) Filed: **May 30, 2025**

(57)

CLAIM

The ornamental design for an inductor package as shown and described.

DESCRIPTION

FIG. 1 is a top, front, right perspective view of an inductor package in accordance with our design;
FIG. 2 is a bottom, rear, left perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof; and,
FIG. 8 is a bottom plan view thereof.
